UNITED STATES PATENT OFFICE.

ADOLPH RYDQUIST, OF ROCHESTER, NEW YORK.

COIN-CONTROLLED VENDING-MACHINE.

1,235,247.

Specification of Letters Patent.

Patented July 31, 1917.

Application filed October 2, 1915. Serial No. 53,680.

To all whom it may concern:

Be it known that I, ADOLPH RYDQUIST, of Rochester, in the county of Monroe and State of New York, have invented certain new and useful Improvements in Coin-Controlled Vending-Machines; and I do hereby declare the following to be a full, clear, and exact description of the same, reference being had to the accompanying drawings, forming a part of this specification, and to the reference-numerals marked thereon.

My present invention relates to coin controlled vending machines and it has for its object to provide a machine which is especially adapted for the selling of small packages of goods such as gum, candy and the like, said machines being adapted to be mounted in public places. To these ends the machine embodies certain novel features in the construction of the shell or casing which in addition to adding to its attractiveness, lessens the possibility of damage to the interior mechanism and the unauthorized removal of the goods. Further the invention comprises an improved mechanism for delivering the goods upon the insertion of coins of the proper denomination, said mechanism comprising features whereby spurious coins, paper disks, washers and the like may be detected and discharged without effecting a delivery of goods or interfering with the operation of the machine. To these and other ends the invention consists in certain improvements and combinations of parts, all as will be hereinafter more fully described, the novel features being pointed out in the claims at the end of the specification.

In the drawings:

Figure 1 is a front elevation of the machine constructed in accordance with my present invention, a portion of the front of the machine being broken away;

Fig. 2 is a vertical sectional view taken on the line 2^x—2^x of Fig. 1;

Fig. 3 is a side elevation;

Fig. 4 is an enlarged rear view of one edge of the casing;

Fig. 5 is a horizontal sectional view taken on the line 5^x—5^x of Fig. 3;

Fig. 6 is a detail sectional view taken on the line 6^x—6^x of Fig. 4;

Fig. 7 is a detail horizontal sectional view taken on the line 7^x—7^x of Fig. 6;

Fig. 8 is a detail sectional view taken on the line 8^x—8^x of Fig. 4;

Fig. 9 is a detail sectional view on the line 9^x—9^x of Fig. 3 showing the locking projection which holds the removable upper section of the case in position;

Fig. 10 is an enlarged sectional view taken on the line 10^x—10^x of Fig. 1 showing the coin controlled mechanism and goods ejecting devices, the parts being in their normal position;

Fig. 11 is a similar view showing the position of the goods ejector upon the insertion of the proper coin when the parts are advanced into ejecting position;

Fig. 12 is a view similar to Fig. 11 taken on the section line 10^x—10^x of Fig. 1 showing the parts in partially operated position;

Fig. 13 is a detail plan view showing the goods ejector taken on the line 13^x—13^x of Fig. 10;

Fig. 14 is an end elevation of the carriage supporting the coin mechanism and goods ejector;

Fig. 15 is a rear elevation of the coin mechanism, the rear cover plate being removed;

Fig. 16 is a horizontal plan view taken on the line 16^x—16^x of Fig. 10;

Fig. 17 is a detail horizontal view showing the position of the coin testing devices at the beginning of their inward movement;

Fig. 18 is a similar view showing the position of said parts as they approach the limit of their inward movement at the instant the coin is deposited;

Fig. 19 is a top plan view of the magazines in which the goods to be delivered, are supported, and

Fig. 20 is a detail horizontal sectional view taken on line 20^x—20^x of Fig. 2.

Similar reference numerals throughout the several views indicate the same parts.

Machines of the character to which my invention is directed are mounted in exposed places where they are most accessible to the public, such as store fronts, street corners, railway stations and similar localities and for this reason it is essential that the casing of the machine shall be durably constructed, weather proof and of such a character as to prevent being easily damaged by persons maliciously inclined. In carrying out my present invention I have provided a construction of casings which is especially adapted to be made of sheet metal, the parts being so arranged that they may be constructed cheaply and easily assembled. The

casing generally described comprises two parts, a base A, which may be mounted upon a pedestal or attached to a wall or similar support, and which contains the coin mechanism and magazines. The other 5 part is the removable closure or cover B which is detachable to afford access to the interior mechanism and is held in place by interlocking projections coöperating with the base, one of which is a key controlled lock. 10 The base A of the machine comprises the back plate 1, at each side of which, at its bottom edges, are the sides 2—2 formed by bending sheet metal plates into the shape shown in Fig. 7, providing them with inner 15 surfaces 2^a and outer surfaces 2^b, the former being connected to the forwardly projecting flange 1^a of the back 1, while the latter is provided with a flange member 2^c which is bent inwardly to abut the outwardly 20 turned flange 3^b carried by the inner surface 2^a, the abutting members being preferably connected by spot-welding. The opening between the surfaces 2^a and 2^b at 25 the top thereof is closed for the greater part of its length by a plate 2^d preferably held in position by spot-welding. The bottom of the base is formed by castings 3 located beneath the side walls 2—2 to which 30 they are interlocked by grooves in their upper surfaces which receive the edges of the walls 2^a and 2^b and screws 3^a which enter flanged pieces 3^b between said walls. These castings are provided at their forward 35 ends with inwardly extending projections 3^c to which the lower front portion 4^b of the chute 4 is attached by means of suitable screws 4^a, said portions terminating in a rearwardly extending flange 4^c, upon which 40 rests the bottom plate 5, the rear edge thereof of having a flange 5^a extending upwardly by which it is secured to the back 1. The sides of the bottom of the chute are supported on shelves 5^d which extend inwardly 45 from the sides of the casting 3. The chute 4 along which the goods descend is carried upwardly and secured to the back 1 at a point above the place where the goods are ejected by the coin controlled mechanism as 50 shown in Fig. 2. At its lower end the chute is formed with a transverse rib or projection 4^a which is adapted to arrest the movement of the goods descending in the chute. Extending between the sides 2—2 is a 55 mechanism support 6 comprising a metal plate having formed on the bottom thereof a roll 6^a engaging with a circular projection 6^b on a casting 6^c which contacts with the lower front of the mechanism case as 60 shown in Fig. 2. The top of the casting is recessed to receive a rearwardly and downwardly inclined flange 6^d on the metal plate. The front wall 14 of the mechanism casing 65 extends down into engagement with the metal plate for the purpose of holding the

casing against rearward displacement. The ends of the casting 6^c are provided with spaced projections 6^e extending through the inner walls 2^a of the sides 2 preferably in engagement with the outer walls 2^b. The 70 projections 6^e are adapted to support the casting 6^c and the flanged members 3^b with which the screws 3^a are connected for the purpose of securing the sides 2 within the grooves formed in the casting 3. 75

The section B of the casing comprises the front wall 7, the edges of which are turned rearwardly to form the sides 7^a, the rear edges of which are bent inwardly as indicated by 7^b to form connecting members 80 for the flanges 7^c. The front and side walls of the casing rest upon a casting 8 having on its upper edge a flange 8^a lying within the front and side walls to which the walls are attached by screws 8^b. Extending downwardly and at the outer edge of the casing is a flange 8^c which surrounds the upper edges of the side walls 2—2. Downwardly extending projections 7^d are positioned at the rear corners of the bottom of the side 90 walls 7^a of the cover B for the purpose of engaging the inner faces of the bottom side walls 2^a for holding the bottom of the casting B in proper position upon the casing A. The forwardly extending flanges 7^c and the connecting members 7^b of the sides 7^a are cut or notched as shown at 7^e in Figs. 4 and 8 for the purpose of receiving the head 1^b and shank 1^c of a stud 1^d carried by the flange 1^a of the back 1 for the purpose of 95 providing means for securing the top of the closure B in position upon the flanges 1^a. The back 1 and flanges 1^a are extended up a considerable distance above the closure A to which the flanges are secured by means of 100 suitable screws 1^e, the inner walls 2^a of the sides 2 being slightly depressed at their rear edges to receive said flanges as shown in Fig. 7. The top edge of the closure B is provided with a cover plate 8^d spaced 105 slightly above the closure, the side and front edges of which are rolled or bent downwardly to embrace the front wall 7 and the side walls 7^a, the rolled edges being provided with openings 8^e to allow for the circulation of air through the casing. Underlying the plate 8^d is a top flange 8^f projecting forwardly from the upper edge of the back 1 having a downwardly turned extremity 8^g forming a shoulder with which 110 the bolt of a key lock 9 coöperates. On the front of the cover is a mirror 10 and below the latter is a glass covered sight aperture 11 permitting a view of the goods contained in the machine, to be had, access to the latter being prevented by a suitable grating 12. 115 In illustrating the coin controlled goods delivering mechanism I have shown these parts arranged in sets of two each, but it will be understood that one or more of 120

these mechanisms may be arranged in a single casing, but as these parts are duplicated, a description of one will suffice for all. Each set of two mechanisms is supported as a unit in a frame comprising side walls 13—13 and front and rear walls 14 and 15 which are so shaped that the mechanism may be carried on the support 6 as shown in Fig. 2. The walls 13, 14 and 15 constitute a mechanism casing within which is supported the sliding carriage on which the coin mechanism and the goods ejectors are mounted. This carriage comprises two parallel flanges 16 and 17 which are spaced apart, on the plate 18 which is moved inwardly by a push rod 19 against tension of a comparatively heavy spring 20 which yields only when the carriage reaches the limit of its inward movement in the event continued pressure is applied to said rod. The restoring of the carriage to its normal position when pressure is removed from the rod 19 is assured by a spring 21 housed in a tube 22 and engaging a finger 23 on the plate 18 which projects through a slot in the tube. The goods sold by the machine are contained in the magazines located above and in rear of the normal position of the carriage and supported upon the latter are ejecting devices which, when brought into operation, as a result consequent upon the insertion of a coin of the proper dimensions followed by movement imparted to the carriage through the medium of the push rod 19, are adjusted into operative position so as to engage and discharge the lowermost packages of the stacks of goods in the magazines. The ejectors are formed of metal stampings comprising the plates 24, the forward edges of which are bent upwardly forming pushers 25, while the rear ends 26 are passed through the apertures 18^a in the plate 18 to form pivotal connections therewith and depending from each ejector is an arm 27, the end of which projects into a slot or aperture in a lever 28 pivoted to a stud 29 on the lower platform 17 of the carriage. The other end of the lever 28 extends forwardly as indicated at 28^a to the front edge of the platform 17, where it projects laterally and is provided with a projection 30 which carries one end of a coil spring 31 which serves to lock the lever 28 on its pivot and to normally hold it in the position shown in Fig. 16 which insures the ejector being held in its lowermost or retracted position as shown in Fig. 10. When a duplicate arrangement of coin mechanisms and ejectors is mounted upon a single carriage a spring 31 is connected to two of said levers, which arrangement permits either or both of them to be operated either independently or simultaneously.

The lever 28 forms part of the coin controlled mechanism and extends in rear of and at one side of the path of movement of the coin which passes onto its seat in front of the pivot 29 after traversing the chute leading thereto which extends from the coin slot 32 in the front plate 14 and comprises the spaced guides 33, arranged above the carriage, and the slot 34 in the upper plate 16 of the latter together with the spaced fingers 35 and 36, (see Figs. 13 and 14). The lower platform 17 of the carriage is provided with an aperture in which the coin is moved while it is performing its function of transmitting motion to the ejector and through which it is finally deposited, but until the ejecting operation has been completed the coin rests upon a seat formed by the shorter side of an aperture or slot 37 in a gage plate 38 which is of a length less than the diameter of a proper coin or check, the longer side of the slot being of a greater length than the coin and adapted to discharge the same under predetermined conditions, the gage plate being pivoted on a stud 29. The aperture or slot 37 is formed in the shape shown to provide an inner shoulder 39 and a rear V-shaped edge 40 which permits these parts to be made so as to accurately gage the diameter and thickness of the coin, which when held thereon co-operates with a projection 28^b on the portion 28^a of the lever. The gage plate 38 is also provided with a downwardly extending projection or stud 38^a lying in a cam groove on a bracket 41 supported on the side wall 13. The cam groove at its outer end extends laterally as indicated in dotted lines at 41^a to impart a slight rotary movement to the gage plate immediately upon the commencement of the inward movement of the main carriage and it curves inwardly to the point 41^b, where at the time when the carriage approaches the limit of its inward movement, said gage plate 38 is rocked so as to carry the shoulder 39 in the opposite direction and well out of alignment of the lower end of the coin chute. Expressing the movement of the gage plate in other terms, it may be said, by referring to Fig. 16, that the motion imparted to it by the outer end of the cam slot carries the coin toward the left hand side of its normal position to actuate the ejector into operative position, and when rocked in the opposite direction by portion 41^b of the cam slot it moves the shoulder 39 to the right hand side of said normal position for the purpose of discharging the coin. The gage plate 38 is further provided with the shoulder 39^a against which the coin is held in light contact by a leaf spring 42 carried on the stud 42^a on the lever 28 and in front of the shoulder 39 is a step or enlargement 37^a of the recess 37. Now it will be seen that when the gage plate 38 is moved toward the

right hand side of the plane of the coin chute the coin will be carried into contact with the fixed abutment 36 which, acting as a stop, will permit the shoulder 39 to be carried from beneath the periphery of the coin, the edge of which passing into the recess 37^a will fall through the aperture in the platform 17 of the carriage into the money box 43.

From the arrangement of the parts above described it will be seen that the coin is supported at its edges by the opposing shoulders of the gage plate 38 and that it is held from dislodgment thereon momentarily by the spring 42 until the coin engages the finger 28^b on the lever 28, after which it imparts movement to said lever rocking the latter upon its pivot 29 and raising the ejector 24 into ejecting position, as shown in Fig. 12, where it is held until the goods are deposited as shown in Fig. 11. Thereafter the gage plate swings laterally permitting the ejector to be restored to its normal position and finally causing the coin to be deposited before the carriage is restored to its normal position by the action of the spring 21. The projection 28^b tests the coin and in the event a washer has been inserted, said projection enters the aperture therein and no movement of the ejector takes place. The spring 31 places sufficient tension upon the lever 28 and offers resistance against the movement of the projection so that a paper disk will either be perforated or crumpled, so that movement is not imparted to the ejector.

The discharge of the goods from the magazines can be facilitated and the depth or thickness of the machine reduced by providing on the lower end of the magazine, the downwardly and rearwardly extending plate 44 and in rear of the magazine a similar plate 45 which is curved or arched slightly to provide a space in which square packages may turn during the time they are being pushed out of the magazine by the ejector 25 and to assist in this turning movement, I provide a light leaf spring 46 arranged on the outer side of the plate 45 and having the end 46^a projecting through an aperture in said plate and lying in such a position that it engages the upper edge of the package and serves to force the latter downwardly toward the plate 45 at the time when it is leaving the bottom of the magazine as shown in Fig. 11.

I claim as my invention:

1. A check controlled device comprising a movable carrier and a gage plate mounted thereon provided with an opening, one side of which is longer than the other, the shorter side being adapted to receive and the longer side to discharge a check, an actuator, and means for operating the actuator upon the operation of the carrier to shift the discharge side

of the opening in the path of the check after a predetermined movement of the gage plate has been effected.

2. A check controlled device comprising a movable carrier and a gage plate mounted thereon provided with a slot at one side of which is formed a shoulder adapted to receive one edge of a check the other side of the slot being of sufficient length to discharge the check, means for moving the gage plate upon movement of the carrier to position the discharge side of the slot in the path of the check.

3. A check controlled device comprising a movable carrier and a gage plate mounted thereon movable relatively to the carrier and provided with a slot, one side of which is adapted to receive and the other to discharge a check, means for holding the check in the receiving side of the slot a predetermined length of time, and means for moving the gage plate upon movement of the carrier to position the discharge side of the slot in the path of the check.

4. A check controlled device comprising a movable carrier and a gage plate mounted thereon provided with a slot, one side of which is of greater length than the other, the shorter side constituting means for receiving and holding a check and the longer side for discharging said check, and means for operating the gage plate upon the operation of the carrier to shift the discharging side of the slot in the path of the check after a predetermined movement of the gage plate has been effected.

5. A check controlled device comprising a movable carrier and a gage plate mounted thereon provided with a slot, one side of which is of greater length than the other, the shorter side constituting means for receiving and holding a check, and the longer side for discharging said check, means for operating the gage plate upon the operation of the carrier, and means for holding the check in the shorter side of the slot during a predetermined movement of the gage plate, the complete operation of said gage plate effecting the discharge of the check through the longer side of the slot.

6. A check controlled device comprising a movable carrier and a gage plate operatively connected with the carrier and provided with a slot, one side of which is of greater length than the other, the shorter side constituting means for receiving and holding a check and the longer side for discharging said check, a movable member adapted to engage said check and operable thereby upon the movement of the gage plate, and an ejector operatively connected with said movable member.

7. A check controlled device comprising a reciprocating carrier and a gage plate mounted thereon provided with a slot, one

side of which is of greater length than the other, the shorter side constituting means for receiving and holding a check and the longer side for discharging said check, 5 means for operating the gage plate upon the operation of the carrier to shift the discharging side of the slot in the path of the check after a predetermined movement of the gage plate has been effected and means 10 operatively associated with the check to prevent the carrier from returning to normal position before the discharge of said check is effected.

8. In a check controlled apparatus, the 15 combination with a movable check carrier having a recess therein to receive a check, of a gage plate operatively connected with the carrier provided with a slot one side of which is of greater length than the other, the 20 shorter side of the slot being normally in position to receive a check through the recess, the longer side of the slot being adapted to discharge said check upon a predetermined movement of the gage plate, a movable 25 member for engaging the check adapted to be operated thereby upon movement of the gage plate, and an ejector operatively connected with said movable member.

9. In a check controlled apparatus, the 30 combination with a movable check carrier having a recess therein to receive a check, of a gage plate pivotally mounted upon the carrier provided with a slot, one side of which is of greater length than the other, the 35 shorter side of the slot being normally in position to receive a check through said recess, means for rocking the gage plate when the same is moved by the carrier, a check stop positioned on the shorter side of said slot 40 adjacent thereto, a movable check engaging member on the opposite side of the slot operable through the movement of the check by the movement of the gage plate in one direction, the return movement of the gage 45 plate causing the check to engage said stop until the longer side of the slot is moved into the path of the check to release the same, and an ejector operatively connected with said movable check engaging member.

50 10. In a check controlled apparatus, the combination with a movable check carrier having a recess therein to receive a check, of a gage plate movable with the carrier provided with a slot, one side of which is of 55 greater length than the other, the shorter side of the slot being normally in position to receive a check through the recess and of a length less than the diameter of the check, a check stop positioned on the short side of

said slot adjacent thereto, means for causing 60 the gage plate to first move outwardly and then inwardly beyond its normal position during the movement of the carrier, whereby the check is adapted to engage said stop before the completion of the return movement of the gage plate, so that the longer side of said slot may be positioned in the path of the check to cause the release of the same.

11. In a check controlled apparatus, the 70 combination with a movable check carrier having a recess therein to receive a check, of a gage plate movable with the carrier, provided with a slot, one side of which is of greater length than the other, the shorter 75 side of the slot being normally in position to receive a check through the recess and of a length less than the diameter of the check, a check stop positioned on the short side of said slot adjacent thereto, means for causing 80 the gage plate to first move outwardly and then inwardly beyond its normal position during the movement of the carrier, whereby the check is adapted to engage said stop before the completion of the return movement of the gage plate, so that the longer 85 side of said slot may be positioned in the path of the check to cause the release of the same, and means for holding the check in the short side of the slot during the outward 90 and inward movement of the gage plate.

12. In a check controlled apparatus, the combination with a movable check carrier having a recess therein to receive a check, of a gage plate movable with the carrier provided with a slot, one side of which is of greater length than the other, the shorter 95 side of the slot being normally in position to receive a check through the recess and of a length less than the diameter of the check, a 100 check stop positioned on the short side of said slot adjacent thereto, a movable member for engaging the check on the side opposite to the stop and adapted to be operated by the check upon movement of the gage plate, 105 means for causing the gage plate to first move the check away from the stop and afterward returning the same to engage therewith, said means operating to position the longer side of the slot in the path of the 110 check held by the stop to effect the release of the check, and an ejector operated by said movable check engaging member.

ADOLPH RYDQUIST.
